MACHINE FOR LAYING CONCRETE PAVEMENT

Thomas M. Beatty, Quincy, Ill.

Application October 17, 1951, Serial No. 251,803

2 Claims. (Cl. 94—46)

This invention relates to a machine and method for laying concrete paving and is particularly designed for use in paving highways where the roadbed has been prepared and side forms defining the width of the highway have been set in position.

The primary object of the invention is to provide a unitary self-propelled machine utilizing the side forms as tracks and adapted to continuously lay, tamp and level concrete paving on the roadbed during movement therewith.

Another object of the invention is to provide a machine that by self-generated pneumatic power will be propelled to lay a strip of concrete paving and by the same power will automatically tamp the concrete during the laying operation.

A further object of the invention is to provide a self-propelled machine for the purpose set forth wherein a plurality of transversely aligned inclined pneumatically operated tampers are operable for the machine to tamp the concrete as it is laid during movement of the machine.

Still another object of the invention is to combine in a single machine the cooperative functions of an air compressor, air motor and pneumatic tampers together with means for feeding and leveling the fresh mixed concrete.

Still another object of the invention is to provide a new method or process of pneumatically laying and tamping fresh mixed concrete in strip form along a prepared roadbed to facilitate the laying of concrete paving on highways.

These and other objects of the present invention will appear as the following description thereof proceeds, and in order to more clearly understand the invention, reference may be made to the accompanying drawings in which.

In the drawings:

Figure 1 is a top plan view of the machine mounted on the side forms of a prepared roadbed.

Figure 2 is a front elevation thereof.

Figure 3 is a side elevation of the machine, partly in section.

Figure 4 is a perspective view of the head of one of the pneumatic tampers.

Various machines have heretofore been employed for laying concrete highways with varying degrees of success. The present machine is believed to successfully overcome the defects in the prior developments along this line. The method of using self-generated pneumatic power for laying concrete paving greatly facilitates this operation in road building and the machine itself embodies a unitary arrangement and combination of the various mechanisms for accomplishing the necessary functions compactly assembled to accomplish the final result in an economical and practical manner.

The machine is adapted to travel on tracks formed by the parallel side forms F which define the width of the prepared roadbed upon which the fresh mixed concrete is to be laid. The machine itself comprised a base frame

2

formed preferably of side channel beams 1 and cross channel beams 2, all usually in the same plane. A cross beam is positioned at either end of the side beams and a pair of strengthening cross beams as spaced therebetween.

5 The frame is not quite as wide as the distance between the side forms F.

On axles 3 mounted in bearings 4 on the side beams 1, are main supporting wheels 5 for the machine. Spaced forwardly and rearwardly of the main wheels 5, are 10 smaller supporting wheels 6 and driving wheels 7, mounted on axles 8, trunnioned in the side beams 1. The wheels are of the usual flanged type, being aligned on each side of the frame and adapted to travel on tracks formed by the forms F.

15 Intermediate the axles 3 of the main wheels 5, and formed by cross channel beams 9 positioned on the frame side beams 1, is a subframe upon which is mounted a conventional air compressor assembly C with the usual engine motor M. At the rear of the machine and formed by cross channel beams 10 is another subframe upon

20 which is mounted a pair of air motors A in communication through a pipe 11 which is in turn connected with an outlet 12 from the compressor C controlled by a valve 13. Each air motor is drivingly connected by a chain and sprocket connection 14 with the axle for driving wheels 7 to propel the machine along the tracks when the valve 13 is open.

25 Mounted on the main frame of the machine is a hopper H extending transversely the width of the frame. The rear wall of the hopper tapers to a bottom discharge throat D and the rear wall of said throat forms a swing gate 15, hinged at 16 and adjustable as shown at 17 to vary the size of the discharge opening for the hopper. The lower edge of the gate 15, is flanged rearwardly at 18

30 to spread the material as discharged from the hopper H when the machine is moved forwardly. A finger agitator 19 is positioned in the hopper and may if desired be rotated by means not shown. The front wall and side walls of the discharge throat D may be secured to the respective front cross beams and side beams of the main frame and the throat terminates slightly above the level of the forms F and below the main frame of the machine.

35 The tamping feature of this machine comprises a battery of pneumatic tampers T arranged in horizontal alignment across the front of the machine frame and adapted to be adjustably inclined rearwardly and downwardly from the horizontal for tamping head engagement with the fresh mixed concrete as it is discharged from the hopper. To support the tampers in position there is secured

40 to the front cross bar of the main frame an angle bracket 20 with side wings 21 having arcuately positioned apertures 22 along the curved upper edges of said wings. The upright portion of said angle bracket is secured by fasteners 23 to the front cross bar of the machine. A trans-

45 verse connecting plate 24 is rigidly secured to the body of each individual tamper T to hold them in horizontal spaced alignment. An extending rear edge portion 25 of the plate 24 is hinged at 26 to the front edge of the horizontal portion of angle bracket 20. The ends 50 of the plate 24 are curved upwardly at 26' parallel with the inner faces of the wings 21 and each end 26' is provided with an aperture 27 adapted for alignment with any of the wing apertures 22 when the plate 24 is swung on the hinge 26. A removable pin 28 is provided for interlocking the parts in any desired angular position of the plate 24 and tampers T.

55 Air is fed to the tampers T by means of an outlet conduit or pipe 29 at the front end of the air compressor C, valved at 30. A conduit or pipe 31, extends down and then transversely of the machine as shown in Figures 1 and 3, and then forwardly as shown at 32. The terminal extends transversely across the front of the machine as

shown at 33 and is capped at 34. The pipe portion 33 is adjacent the upper ends of the tampers T and is connected therewith by journalled T couplings or unions 35 in spaced relation as clearly shown in Figures 1 and 3. Of course the portion of the pipe or conduit 33 engaged by the couplings 35 is in communication therewith, by means, not shown. As the tampers T are supported on the frame by the means shown no appreciable weight is carried by the section 33 of the pipe or conduit and the purpose of the couplings is to provide a journalled connection for the air feed to each tamper.

As the tamper bodies are spaced across the front of the machine there is provided angle heads 36 for each tamper of such a width that each head is closely spaced with respect to adjacent heads, so there is no appreciable break in the tamping action on the concrete at the front of the machine. Each head 36 is angular to provide a tamping portion 37 and an upper flange 38. The rear face of the portion 37 is grooved at 39 and has a central rearwardly extending stud 40 for engagement in the body of the tamper in the usual manner.

For the purpose of leveling the surface of the concrete between the forms F there is carried by the machine frame a leveling plate P, either flat or crowned that is adjustably mounted on the machine. The plate is approximately the full width of the machine. Its front edge is positioned slightly to the rear of the discharge throat D of the hopper H and it extends rearwardly a sufficient distance to level off the top surface of the concrete.

The plate P is supported on the intermediate cross beams 2 and side beams 1 of the main frame of the machine by hanger stirrups 41 engageable on rods 42. The stirrups are vertically adjustable by cam levers 43. Four of these assemblies are provided adjacent each corner of the plate P and they are identical. The lower end of each stirrup is secured to the plate by welding or the like and the portions adjacent the plate are threaded to receive lock nuts 44 to lock each support in the desired adjusted position.

In operation the machine is placed on the tracks formed by the forms F and the hopper H, filled with a batch of fresh mixed concrete. With the air compressor C operating in the usual manner upon opening the valve 13, compressed air will enter the motors A and through the chain and sprocket connection 14 will rotate the drive wheels 7 to propel the entire frame along the tracks. The gate 15 is opened the required distance to feed the concrete from the hopper H to the prepared roadbed between the forms F. When the valve 30 is open air from the compressor is fed to the tampers T through the means described. The battery of tampers and heads 36 have been previously set at the desired angle with respect to the horizontal and are inclined downwardly and rearwardly so as to engage and tamp the concrete as it is discharged from the hopper at a point adjacent and in front of the throat D. This action will tamp and set the fresh mixed concrete as the machine is propelled along the forms. The adjustable leveling plate P will level the top surface of the laid concrete bed to the configuration and height desired.

The motor driven air compressor of this machine furnishes the motive power to drive the same and also the power to operate the battery of inclined tampers. After the leveling plate is adjusted it is only necessary to refill the hopper so the laying operation is practically continu-

ous. This method of laying concrete highways greatly simplifies the operation and reduces the same to a simple form that effects considerable economy in labor and effort. The constituent elements of the machine are assembled in a compact relationship with due regard to the essential and cooperative functioning of each that is deemed a material improvement over prior apparatus for this purpose.

Although the improved machine and method for laying concrete paving has been illustrated and described herein to a detailed extent, it will be understood, of course, that the invention, is not to be regarded as limited correspondingly in scope, but includes all variations coming within the terms of the appended claims.

I claim:

1. In a machine for laying concrete paving, a wheeled frame mounted for movement along parallel side forms and over a roadbed, an air compressor on said frame adapted to furnish motive power to propel said frame, a transversely extending hopper carried by said frame to distribute concrete on the roadbed as the frame moves thereover, a plurality of spaced pneumatic tampers for tamping the distributed concrete transversely aligned across the front of the frame and inclined rearwardly and downwardly with respect to the horizontal, a plate rigidly connecting the transversely aligned tampers, a bracket on the front of the frame hingedly connected to said plate, selective interlocking means to hold the plate in various angular positions with respect to the bracket to vary the angle of the tampers, and means to connect the air compressor to the tampers in any adjusted position.

2. In a machine for laying concrete paving, a wheeled frame mounted for movement along parallel side forms and over a roadbed, an air compressor on said frame adapted to furnish motive power to propel said frame, a transversely extending hopper carried by said frame to distribute concrete on the roadbed as the frame moves thereover, a plurality of spaced pneumatic tampers for tamping the distributed concrete transversely aligned across the front of the frame and inclined rearwardly and downwardly with respect to the horizontal, a plate rigidly connecting the transversely aligned tampers, a bracket on the front of the frame hingedly connected to said plate, selective interlocking means to hold the plate in various angular positions with respect to the bracket to vary the angle of the tampers, means to connect the air compressor to the tampers in any adjusted position, and angled heads on said tampers each arranged in closely spaced relationship with the ends of adjacent heads of the transversely spaced tampers.
